UNITED STATES PATENT OFFICE.

FRANK H. WARREN, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

TACK-PULLING APPARATUS.

Application filed January 2, 1925. Serial No. 162.

My invention relates to tack-pulling apparatus, and especially to the work-engaging elements of apparatus employed to remove lasting tacks from shoe-uppers.

In one form of upper-tack-pulling machine, as disclosed, for example, in the application filed on June 10, 1924 in the name of Fred L. Mackenzie, Serial No. 719,076, a pulling member or claw operates over a gage, 10 guard and hold-down member, which extends at one side of a supporting shank, this, in the instance given, being to the right. There also may be an additional hold-down device furnished by a forward projection from the 15 shank. With such apparatus, the line of tacks to be pulled must be advanced toward the gage into co-operation with the pulling member from the same side of the shank and forward projection as that at which the gage 20 is located. Sometimes, however, because of the manner in which the machine is set up, or because of the preference of a particular operator, better results may be obtained by feeding the line of tacks at the opposite 25 angle, or from the left.

My invention has as an object the provision of a machine to the pulling instrumentalities of which the work may be presented from either side. To gain this end, I 30 combine with the tool a work-engaging member serving as a gage, a guard or a hold-down and having an intermediate wall at opposite sides of which the pulling member moves. To arrange the elements in this relation, the 35 pulling member is in sections, separated by a space into which extends a portion of the work-engaging member, as a supporting shank, and also a forwardly projecting hold-down wall. The two sections of the device, 40 without the addition of any independent elements or necessity for adjustment and presenting generally the usual operating conditions, allows the operator to vary the angle of approach of the work to best satisfy his 45 particular needs.

The accompanying drawing illustrates but one of the various possible embodiments of the invention,

Fig. 1 showing, in side elevation, an upper- 50 tack-pulling machine to which my invention is applied;

Fig. 2 illustrating the work-engaging elements of the apparatus in perspective; and

Fig. 3 being a detail top plan view of these elements.

From a standard 10 projects an arm 12, in which a pulling lever 14 is supported upon an oscillatory link 16. Rotatable driving mechanism 18, acting upon the inner end of the lever, imparts the desired movement to it. At the outer extremity of the lever is clamped a pulling tool 20 having the usual depressions 22 constituting a claw and arranged to be moved forward into engagement with the shanks of tacks driven into the work, and then upward along a cyclic path to remove them from said work. This tool is in two sections 24 and 25, spaced from each other by a slot 26, which extends back into the tool from its pulling edge. Each section is of sufficient width to act effectively alone for the pulling of the tacks.

Pivoted at 28 upon the frame-arm 12 is a supporting arm 30, at the outer end of which is an enlargement 32. At one side of this enlargement are formed vertical ways 34 to receive the shank 36 of a member G co-operating with the pulling tool. A slot-and-screw connection 40, between the member G and the supporting arm, permits the height 80 of the member and its relation to the tool to be varied. The shank is so located that it is received by the slot 26, the sections of the tool operating upon opposite sides of the wall furnished by the shank. The member G provides a work-gage, guard and hold-down for both tool-sections, it having sections 38 and 39 respectively co-operating with the tool-sections 24 and 25. Extending at each side of the shank is a substantially horizontal wall 42, into proximity with the forward edge 44 of which the line of tacks T (Fig. 3) to be pulled is advanced. A spring 46, surrounding the pivot of the arm 30, acts to raise the walls 42 into proximity with the tool, yet permits the member G to yield if a tack or other object becomes lodged between these elements. The edge 44, by contact with the tacks, retains them within the effective operating area of the claws. The under sides of the walls 42 determine the upward movement of the work toward the paths of the tool-sections, guarding the upper S against injury by the tool, and also act as abutments to resist the pulling action upon the work. At the outer

extremities of the horizontal walls 42 rise vertical walls 47, beside which the outer sides of the tool-sections move, these portions 47 being to protect the hands of the operator against injury.

To prevent the claw from catching beneath the loose edge *s* of the lasted-over upper, operators customarily thrust the line of tacks *T* for engagement by the tool at an angle to the direction of movement of said tool. If an operator chooses to work from the right when employing the present apparatus, he utilizes the tool-section 24 and its co-operating gage-section 38, the travel of 15 the shoe being as indicated in full lines in Fig. 3. If movement from the left is more convenient, the tool-section 25 and gage-section 39 are employed, the dotted lines in Fig. 3 indicating the position of the work. In 20 either case, the action is the same, the operator bringing forward the tacks successively into proximity with the edge 44 of the section which he chooses and at the desired angle thereto, at which point they are 25 engaged and drawn from the work by the corresponding oscillatory claw-section. To insure the edge *s* of the upper from being caught by either of the tool-sections, the vertical or shank-wall 36 is extended forwardly at 48, being preferably rounded at its outer extremity. This furnishes a hold-down 30 for the edge, common to both operating sections and substantially at right angles to their hold-down walls 42, it acting upon the upper in the same manner, whether the work be at the right or the left. The hold-down 35 48 and the oppositely extending gage edges 44 form recesses toward either of which the line of tacks *T* may be directed as the work 40 is presented to one side or the other of the machine. Such an organization, it will be seen, provides a double-duty machine without the addition of parts or change of position thereof, there being simply an extension 45 of two elements at opposite sides of an element functioning with both.

Having described my invention, what I claim as new and desire to secure by Letters Patent of the United States is:—

- 50 1. In a tack-pulling machine, a movable pulling member, and a work-engaging member having a supporting shank, said pulling member being movable upon opposite sides of the said shank.
- 55 2. In a tack-pulling machine, a movable pulling member provided with pulling sections separated by a space and movable in parallel paths, and a work-engaging member having a wall extending into said space.
- 60 3. In a tack-pulling machine, a pulling member having separate sections, and a work-engaging member provided with a plurality of portions co-operating respectively with the pulling sections, and also provided 65 with a portion common to said sections.

4. In a machine for pulling lasting tacks from shoes, a work hold-down member having an upright wall, and a pulling member having a tack engaging end moving in a cyclic path simultaneously upon opposite sides of the 70 wall to pull a tack presented to the machine at either side of said wall.

5. In a tack-pulling machine, a member having work-hold-down walls lying at an angle to each other, and a pulling member 75 operating at opposite sides of one of the hold-down walls.

6. In a tack-pulling machine, a gage member arranged to limit the approach of the work to the machine and having a substantially vertical wall, and a pulling member provided with claws separated by a space to receive said vertical wall. 80

7. In a tack-pulling machine, a bifurcated tack-pulling claw, and a gage member adjustably mounted in fixed position upon the machine and having a portion dividing said claw. 85

8. In a tack-pulling machine, a claw in which there is a slot, and a work-hold-down 90 member extending into the slot.

9. In a power driven tack-pulling machine for boots and shoes, a support, a shoe hold-down member depending therefrom and arranged to engage the work at its lower end, 95 and a pulling tool having tack-pulling end portions operating repeatedly in cyclic paths at opposite sides of said member adjacent to said end so that the work may be presented in either of two paths angularly related to opposite sides of the shoe-engaging end of said hold-down member. 100

10. In a tack-pulling machine, a support, a member having a substantially vertical shank secured to the support and provided 105 with a gage-edge extending at opposite sides of the shank, and a pulling member having a divided claw operating over the gage-edge at both sides of the shank.

11. In a tack-pulling machine, a support, a member having a substantially vertical shank secured to the support and provided with a forwardly extending hold-down-projection and a gage-edge extending at opposite sides of the projection, and a pulling member having a divided claw operating 115 over the gage-edge at both sides of the shank and projection.

12. In a tack-pulling machine, a support, a member having a substantially vertical shank secured to the support and provided with a gage-edge extending at opposite sides of the shank, and a pulling member having a divided claw operating over the gage-edge 120 at both sides of the shank, said first-named member having vertical walls disposed outside the pulling member at the ends of the gage edges. 125

13. In a tack-pulling machine, a pulling member the effective portions of which move 130

through cyclic paths into and out of contact with tacks presented to one or another portion of said pulling member, and a work-engaging member having a wall on opposite sides of which the effective portions of said pulling member move as the work-engaging member is held in contact with the work.

14. In a tack-pulling machine, a support, 5 a work-engaging member depending from said support and provided with a forwardly

extending holddown member and gage members extending in opposite directions from said holddown member to provide angular recesses toward either of which a line of 15 tacks may be directed, and a tack-pulling member having portions operating at either side of said depending member.

In testimony whereof I have signed my name to this specification.

FRANK H. WARREN.
